UNITED STATES PATENT OFFICE.

JOHN DEWRANCE, OF LONDON, ENGLAND.

MULTIPLE-WAY STOP-VALVE.

1,345,751.

Specification of Letters Patent. Patented July 6, 1920.

Application filed September 23, 1918. Serial No. 255,362.

To all whom it may concern:

Be it known that I, JOHN DEWRANCE, a subject of the King of Great Britain and Ireland, residing at 165 Great Dover street, 5 in the county of London, England, have invented new and useful Improvements in Multiple-Way Stop-Valves, of which the following is a specification.

This invention relates to multiple-way 10 stop-valves adapted for use in readily connecting or disconnecting two or more of a series of vessels, according to prevailing requirements, and consists in an improved method of construction whereby manipulation 15 is simplified and economy in the cost of manufacture effected.

A three-way valve constructed according to my invention is illustrated in the accompanying drawings, whereof Figure 1 is a 20 longitudinal section. Fig. 2 a plan view partly exposing the interior and Fig. 3 an external view looking in the opposite direction; while in Fig. 4 is represented an alternative method of constructing a certain 25 detail hereinafter particularly described.

About a central chamber A are arranged three laterally projecting branches, B, B', B², in each of which is mounted a spring-loaded valve C; two of these branches being 30 arranged opposite one another, while the third or intermediate branch is at right angles to the other two, all being in the same plane. The guide-stem C' of each valve projects into the central chamber A a sufficient 35 distance to admit of its being lifted by any one of three prominent portions of a cam-shaped body D mounted within the central chamber and carried by a stem D' whereby it may be rotated by means of an 40 external attachment E. The latter is preferably three armed as shown; each arm corresponding with and serving to indicate the position of one of the prominent and operative portions of the cam-shaped body 45

D. The cam-stem D' is prolonged beyond the cam D and takes a bearing in the removable cover A' which serves to close the central chamber. Upon the under side of the handle E is formed a projection or boss E' in which is mounted a spring-loaded ball 50 G adapted to bear against the neck of the

valve-casing A in which the cam-spindle D' is mounted. In the plane of the said ball are formed, at certain points in the outer surface of the neck, shallow cup-like depressions G' adapted for the ball to engage with as the latter arrives opposite each depression, thereby offering a moderate resistance to the further rotation of the handle E. The operation of turning this handle is in 55 consequence attended by a series of "clicks" which indicate to the operator the extent to which the cam is turned and assist in determining the final position desired.

For the spring-loaded ball G, a spring-loaded plunger G² may be substituted as illustrated in Fig. 4; the same being formed with a rounded inner extremity adapted to enter and temporarily engage in each of the depressions G' formed in the neck of the 70 valve-casing A, as previously described with reference to the ball G. This method of construction is advantageous in respect of providing against the ball escaping and becoming lost upon the handle being removed from the neck of the valve-casing.

It will also be obvious that, instead of a circumferential cam for operating the valves, a face-cam may be employed; the valve C and the branches B, B', B², wherein they are mounted being in this case arranged parallel with, instead of at right angles to, the cam-stem D'.

A three-way valve of the character above described is particularly appropriate for use 85 in optionally connecting a petrol storage tank with a carbureter or with a service tank, or the latter with the carbureter; but it may be employed for other purposes. Or where the number of vessels to be placed in 90 communication at the option of the user is more than three, the essential elements of the construction may be correspondingly increased in number.

I claim:—

1. A multiple-way stop valve comprising a central chamber, a plurality of branches extending therefrom in angular relation, valves for controlling said branches, said valves having an operative part extending 100 into the chamber and a cam mounted within the chamber, having a plurality of project-

ing points disposed to simultaneously engage in different positions the operative parts of different groups of valves.

2. A multiple-way stop valve comprising a central chamber, three branches so disposed as to define two right angles and an angle of 180° , a valve in each branch, each

valve having an operative part extending into the chamber, a cam mounted in the chamber, having three projecting points disposed to engage, in one position, the three projecting parts of the valves and means for revolving the cam. ¹⁰

JOHN DEWRANCE.
